UNITED STATES PATENT OFFICE.

THADDEUS F. BAILY AND FRANK T. COPE, OF ALLIANCE, OHIO, ASSIGNEES TO THE
ELECTRIC FURNACE COMPANY, OF ALLIANCE, OHIO, A CORPORATION OF OHIO.

CONTAINER FOR ARTICLES TO BE HEAT-TREATED AND THE LIKE.

1,291,717.

Specification of Letters Patent. Patented Jan. 21, 1919.

Application filed June 14, 1918. Serial No. 240,060.

To all whom it may concern:

Be it known that we, THADDEUS F. BAILY and FRANK T. COPE, citizens of the United States, both residing at Alliance, in the county of Stark and State of Ohio, have invented a new and useful Container for Articles to be Heat-Treated and the like, of which the following is a specification.

This invention relates to receptacles or containers for holding small articles manufactured from metal while the said articles are being passed through the heating furnace during the heat treating, annealing or carbonizing process of the articles.

The object of our invention is to form a container for this purpose that will, when used with a plurality of similar containers, be sealed during its transit through the furnace by the next adjacent container.

With these objects in view the invention consists in the novel construction and arrangement of parts, hereinafter described, illustrated in the accompanying drawings, and particularly pointed out in the appended claims, it being understood that various changes in the form, proportions, size and minor details of construction may be made within the scope of the appended claims, without departing from the spirit or sacrificing any of the advantages of the invention.

In the drawings:

Figure 1 is a view illustrating an electric furnace with a plurality of our containers shown passing therethrough.

Fig. 2 is an enlarged perspective view of one of our containers.

Similar numerals of reference indicate corresponding parts throughout the several figures of the drawings.

In the heating of comparatively small articles manufactured from metal, such as small automobile parts and the like, it is necessary that the container be provided in which the articles are placed while in transit through the heating furnace. Heretofore such containers have been made merely in the form of a metal box with a removable lid. It not only requires additional and unnecessary labor to place the lids upon these containers after they have been filled with the articles to be heat treated, but upon emerging from the heating furnace the containers are extremely hot and no small

amount of difficulty is frequently experienced in removing the lids from the containers. Those skilled in the art will appreciate that in the heat treating process of steel the quenching must be done almost instantly after the articles being treated have been heated to a desired temperature. Through the difficulty experienced in removing the lids from the containers it is frequently necessary to run the container with its load of articles through the furnace a second time since the time elapsing after the container emerges from the furnace until the lid can be removed is often great enough to allow the articles to cool too far below the desired temperature.

With the object of overcoming this undesirable feature, we have designed a container which requires no lid. In the drawings 1 indicates a furnace which has an opening at 2 to admit articles to be heated and a similar opening at 3 to permit the discharge of the said articles from the furnace. At 4 is shown a motor connected by a suitable gearing 5 to operate a pusher arm 6 which pusher arm is designed to advance the articles to be heated through the furnace, one container at a time.

Our container is shown at 7 and comprises a receptacle with an opening at 8 arranged so that when a plurality of the receptacles are placed in a train, the opening of each receptacle will be effectually closed by the next adjacent receptacle. It will be obvious that by this construction no lid will be necessary upon the container.

This last named apparatus, *viz*: tilting platform and quenching bath forms no part of our invention and is therefore not shown upon the drawings, it being mentioned here simply to illustrate one advantage of our container.

Having fully described our invention what we claim as new and desire to secure by Letters Patent, is:

1. A process of heat treating metal articles comprising placing the said articles in containers, passing the said containers in a continuous train through a heating chamber, each container in the said train forcing the preceding container ahead of it through the heating chamber and forming a closure for the said preceding container.

2. A process of heat treating metal

articles comprising placing the said articles in open ended containers, placing the said containers in a continuous train, each container forming a complete closure for the 5 open end of the next adjacent container and passing the said continuous train of containers through a heating chamber, each

container in the said train acting to force the preceding container ahead of it through the heating chamber. 10

In testimony that we claim the above, we have hereunto subscribed our names.

THADDEUS F. BAILY.
FRANK T. COPE.
